UNITED STATES PATENT OFFICE

ROLLA B. FERREBY, OF LOS ANGELES, CALIFORNIA

CENTRIFUGAL PROPELLER FOR DIRIGIBLE BALLOONS

Application filed January 14, 1929. Serial No. 332,537.

My invention is a centrifugal propeller for dirigible balloons.

My invention pertains to the type of propulsion of a dirigible balloon in which a propeller is mounted on the nose of the balloon and by the centrifugal action in throwing the air outwardly, causes the forward movement of the balloon. Various factors which influence the efficiency of such a type of propeller are in the form of the blades and also the general shape of the propeller as a whole, together with the constructional shape of the nose of the dirigible balloon and its stream line form.

In the operation of the centrifugal type of propeller mounted on the nose of a dirigible balloon, it appears that the propeller throwing the air outwardly by centrifugal force and as it can only suck air in at the center of rotation in front of the nose of the balloon, creates a partial vacuum in front of the nose. The outwardly blown air instead of transversing outwardly in the plane of the propeller, follows the curvature of the nose and the stream line form of the dirigible, the balloon as a whole developing a forward motion varying in speed apparently with the volume of air thrown out by the centrifugal force and the velocity of such air.

An object of my invention is in the construction and mounting of such a propeller so that a large amount of air is thrown outwardly by the centrifugal force and this air has a high velocity.

Another object of my invention is to prevent the escape of air from being acted on by the propeller blades so that these blades positively act on a volume of air coming within their sweep and reduce the eddy currents which interfere with the flow of air outwardly on the blades.

My invention may be considered as an improvement on my patent application for a centrifugal blower for dirigible balloon Serial No. 283,347 filed June 6, 1928.

A further object of my invention is in making the propeller blades somewhat trough shaped in cross section and preferably increasing the width of the trough from the base to the tip of the blades.

Another object of my invention is in mounting the blades at a slight tilt so that the leading edge of a blade is positioned slightly rearwardly of a portion of the trough. The forward portion of the blade therefore functions somewhat as the camber on a propeller, creating a slight vacuum by the flow of air on the leading or forward surface.

In constructing my invention I utilize a suitable type of hub which may be secured to the propeller shaft and preferably has a series of substantial spokes. The blades are riveted or bolted to these spokes and each blade is of a trough-like construction with the open portion of the trough facing in the direction of rotation. The forward side of each blade, that is the side towards the direction of travel of the dirigible balloon, is positioned slightly ahead in the direction of rotation than the rearward edge of each blade, that is on the opposite side of the trough and the leading edge is also turned slightly in or backward from the body of the blade so that the forward edge of the trough is slightly rearwardly of the line of rotation of the forwardmost part of the blade. A suitable cover or spinner is placed on the hub in closing the spokes and the securing devices for the blades and giving a stream line form.

The rear portion of the blades are given a concave curvature following the shape of the nose of the dirigible balloon and are designed to have but slight clearance so that all of the air operated on by the propeller will be thrown out by centrifugal force. The blades may be designed with a large end out, that is at the tip and a small root connected to the hub; or they may be constructed in an opposite manner with a relatively large root and a small tip.

My invention is illustrated in the accompanying drawings, in which:

Figure 1 is a front elevation of substantially half of a propeller, showing a type with the blades having the tips larger than the root;

Fig. 2 is a side elevation of a propeller shown in Fig. 1;

Fig. 3 is a rear view of the propeller of Figs. 1 and 2;

Fig. 4 is a section on the line 4—4 of Fig. 1 in the direction of the arrows;

Fig. 5 is a front elevation of an alternative form of propeller, in which the tip of the blade is smaller than the root;

Fig. 6 is a side elevation of a propeller of Fig. 5;

Fig. 7 is a rear elevation of a propeller of Figs. 5 and 6;

Fig. 8 is a section on the line 8—8 of Fig. 5 in the direction of the arrows.

Referring first to Figs. 1 through 4, the propeller shaft 11 has a substantial hub 12 secured thereto, this being the hub of the propeller, and on this hub I have a plurality of spokes 13 of a substantial character and of suitable shape. To these spokes are secured the blades designated generally by the numeral 14 of the propeller and on the front there is a cone-shaped spinner 15 for the purpose of deflecting the air and giving a more or less stream like form and to enclose the spokes and the hub.

The characteristics of the blade 14 is the trough-like construction indicated by the numeral 16 and the leading edge 17 is forward of the trailing end 18 of each of the blades. The troughs may be of different depths. The extreme forward surface 19 of each of the blades considered in the direction of movement of the balloon is positioned slightly forward of the leading edge 17. The line 20 designates the plane of rotation of the extreme forward portion 19 of the blade and 21 the plane of the rotation of the leading edge 17, these being considered of any particular cross section. Therefore the surface 19 may be considered as having a lead designated by the measurement 22 in front of the leading edge 17. The inner portion 23 of the trailing edge 18 is carried slightly forward of the inner portion 24 of the leading edge 17.

The trailing edge also has a concave curvature as indicated at 25, conforming somewhat to the curvature 26 of the nose 27 of the dirigible balloon. In this type of blade the root 28 is of lesser size than the tip 29 of the blade and if desired the trough may vary in depth from the root to the tip and manifestly it varies in width between the leading and trailing edges from the root to the tip of the blade.

In the construction illustrated in Figs. 5 through 8, the blade has the root portion 30 of greater size than the tip portion 31. The leading edge 32 is forward of the trailing edge 33 and the leading edge is slightly back from the extreme forward portion 34 of the body of the blade. The trough section 35 may vary in depth from the root to the tip 36 of the blade and the distance between the leading and trailing edges decreases from the root to the tip. The trailing edge in this case has a concave curvature 38 conforming to the curvature of the forward surface 37 of the nose 38 of the dirigible balloon. This

construction also necessitates the forward portion of the blade having a convex curvature 39 on account of the blades tapering from the root to the tip and following the curvature of the nose of the dirigible balloon.

In the operation of my propeller, the direction of rotation is so that the trough catches the air and such air is held in the trough while it travels longitudinally of the blade from the root towards the tip. As the velocity of the tip of the blade is considerably greater than that of the root, the air becomes highly compressed and is thrown outwardly by centrifugal force so that the flow of air from each blade more or less acts as distinct outwardly flowing columns. As the blades are rotating rapidly, these merge together and cause a direct outward movement of air considered radially from the axis of rotation. As the air can only be drawn into the propeller from the front, this creates a partial vacuum, tending to draw the dirigible balloon ahead.

It has been found that the stream of air clings to or follows the surface of the dirigible balloon when this is properly stream lined somewhat in the manner as set forth in my patent application above mentioned. The combined action of the centrifugal air blast is to move the dirigible balloon in a forward direction.

The feature of having the leading edge 17 slightly rearward or towards the nose of the balloon in relation to the extreme forward portion 19 of the blade, appears to give this portion a spacious or aerofoil effect, such as the upper surface of the conventional aeroplane wing creating a partial vacuum in front of the leading edge of the trough-like blade, functioning to draw the dirigible balloon forwardly. In addition, on account of the forward motion of the translation of the propeller as a whole, the leading edge of the trough-like blades catches the air and does not allow this to form eddies blowing around the leading edge on to the back surface of the blade.

In the construction of Figs. 1 through 4, in which the tip of the blade is wider than the trough, the function is to spread the column of air discharged from each blade in a fore and aft direction and thus give outwardly moving air streams which may be considered as comparatively shallow and having a lesser velocity than when the tip 120 of the blade is smaller than the root as in Figs. 5 through 8. In this latter construction the air blast following the trough-like blades is more or less concentrated adjacent the tip of the blades and discharges with an outward high velocity, and moreover, on account of the rearward curvature of these blades, the blast of air is directed rearwardly along the nose of the dirigible balloon.

Various changes may be made in the prin-

ciples of my invention without departing from the spirit thereof as set forth in the description, drawings and claims.

I claim:

1. A propeller for dirigible balloons having a plurality of centrifugally acting trough-shaped blades adapted to be driven by a rotary shaft, each of said blades having the leading edge forward of the trailing edge considered in the direction of rotation and the leading edge being turned rearwardly considered in relation to the forward movement of the propeller from the side structural part of the trough of each blade.

10 2. A propeller for dirigible balloons as claimed in claim 1, the trough of each blade varying in cross section from the root to the tip of the blade.

20 3. A propeller for dirigible balloons as claimed in claim 1, the trailing edge of the blade being free of a support and having a concave curve in a fore and aft direction.

25 4. A propeller for dirigible balloons, comprising a plurality of centrifugally acting trough-like blades with means to secure same to a rotary shaft, each of said blades having a leading and a trailing edge, the trailing edge being concave considered in a radial direction, the leading edge of the blades being forward of the trailing edge considered in the direction of rotation of the blades.

30 5. A propeller for dirigible balloons as claimed in claim 4, said leading edge being turned rearwardly considered in the direction of the forward movement of the propeller from the side of the trough of each of the blades and the trough of each of the blades varying in cross section from the root to the tip.

35 40 6. In a device as described, the combination of a structural portion of a dirigible balloon having a convexly shaped nose, a centrifugally acting propeller mounted on a rotatable shaft extending axially through said nose, the propeller having trough-like blades, said blades having a leading and a trailing edge, the trailing edge being curved to conform to the shape of the nose of the balloon and rotating in close proximity to such convex nose.

45 50 7. In a device as described, the combination of a structural portion of a dirigible balloon having a convexly curved nose, a propeller shaft extending through the nose and a propeller mounted thereon, said propeller having trough-like blades, the center line of each blade being substantially radial to said shaft, each blade having a leading and trailing edge, the trailing edge conforming to the convex shape of the nose of the balloon and rotating in close proximity to such convex nose.

55 60 8. In a device as described, the combination of a structural portion of a dirigible balloon having a convexly curved nose, a

propeller shaft extending through the nose and a propeller mounted thereon, said propeller having trough-like blades, the center line of each blade being substantially radial to the shaft, each blade having a leading and trailing edge, the trailing edge conforming to the convex shape of the nose of the balloon and the leading edge being ahead of the trailing edge in the direction of rotation and rotating in close proximity to such convex nose.

70 9. In a device as described, as claimed in claim 8, the leading edge of the blade being positioned slightly rearwardly of the leading side of the trough-like blade considered in the direction of the forward movement of the propeller through the air.

75 80 10. A propeller for dirigible balloons comprising a shaft having a plurality of centrifugally acting trough like blades secured thereto, each of the blades having a leading and a trailing edge, both of said edges being free of support, the sole support of the blades being the connection to the shaft, and the said trailing edge being concave considered in the fore and aft direction of the movement of the propeller as a whole through the air.

85 90 95 In testimony whereof I have signed my name to this specification.
